(57) **CLAIM**

The ornamental design for a part of baby carriage frame as shown and described.

DESCRIPTION

1. Part of baby carriage frame
2. Part of baby carriage frame
3. Part of baby carriage frame
4. Part of baby carriage frame
- 1.1 : Perspective
- 1.2 : Front
- 1.3 : Back
- 1.4 : Left
- 1.5 : Right
- 1.6 : Top
- 1.7 : Bottom
- 2.1 : Perspective
- 2.2 : Front
- 2.3 : Back
- 2.4 : Left
- 2.5 : Right
- 2.6 : Top
- 2.7 : Bottom
- 3.1 : Perspective
- 3.2 : Front
- 3.3 : Back
- 3.4 : Left
- 3.5 : Right
- 3.6 : Top
- 3.7 : Bottom
- 4.1 : Perspective
- 4.2 : Front
- 4.3 : Back

(Continued)

4.4 : Left**4.5** : Right**4.6** : Top**4.7** : Bottom

1.1 is a perspective view of a first embodiment of part of baby carriage frame; **1.2** is a front view thereof; **1.3** is a back view thereof; **1.4** is a left view thereof; **1.5** is a right view thereof; **1.6** is a top view thereof; **1.7** is a bottom view thereof; **2.1** is a perspective view of a second embodiment of part of baby carriage frame; **2.2** is a front view thereof; **2.3** is a back view thereof; **2.4** is a left view thereof; **2.5** is a right view thereof; **2.6** is a top view thereof; **2.7** is a bottom view thereof; **3.1** is a perspective view of a third embodiment of part of baby carriage frame; **3.2** is a front view thereof; **3.3** is a back view thereof; **3.4** is a left view thereof; **3.5** is a right view thereof; **3.6** is a top view thereof; **3.7** is a bottom view thereof; **4.1** is a perspective view of a fourth embodiment of part of baby carriage frame; **4.2** is a front view thereof; **4.3** is a back view thereof; **4.4** is a left view thereof; **4.5** is a right view thereof; **4.6** is a top view thereof; and **4.7** is a bottom view thereof. The broken lines depict portions of the part of baby carriage frame that form no part of the claimed design.
